WILLIAM MCKAY, OF NEWBURYPORT, MASSACHUSETTS.

Letters Patent No. 94,018, dated August 24, 1869.

IMPROVEMENT IN SAIL-HANKS.

The Schedule referred to in these Letters Patent and making part of the same.

To all persons to whom these presents may come:

Be it known that I, WILLIAM MCKAY, of Newburyport, of the county of Essex, and State of Massachusetts, have invented a new and useful Improvement in Sail-Hanks; and do hereby declare the same to be fully described in the following specification, and represented in the accompanying drawings, of which—

Figure 1 is a front elevation;

Figure 2, a side view;

Figure 3, a longitudinal section; and

Figure 4, a transverse section of it.

This hank has its body A formed of wood, and in shape like an ox-bow, there being arranged between the two legs *a a* of the bow, a roller, B, formed as represented.

This roller rests and revolves on a pin or spindle, C, which extends across the bow and into both legs of it, the spindle at its ends resting against the legs of a bowed guard or metallic strap, D.

This guard D, shaped as shown, spans the legs of the bow A, and enters recesses made therein to remove its legs, which are confined to the legs of the bow A by two or any other suitable number of screws, S S, which go through the guard and screw into the legs of the bow A.

Metallic rivets *b b* are inserted through the legs of the bow A, and above and against the spindle C. These rivets serve not only to insure the legs against being split, but they act as supporters to the spindle, to prevent it from wearing the legs.

The guard, by being carried around the ends of the bows A, and from one to the other, and in front of the roller, answers not only to straighten the bow, but to prevent a jib next adjacent to that to which the hank may be affixed from catching against and being chafed by the ends of the bow.

When this hank is in use, the middle of its bow A

is to be fastened to the sail by a seizing going through the sail and around the middle part of the bow. This is preferable to an eye to the hank to open, as, in case of danger of loss of the sail during tempestuous weather, the seizing can be cut by the knife of a sailor quicker than he can remove the roller or open the hank, so as to detach the sail from the stay. Thus, with my hank, he will be able to save the sail, when with a hank as made with its body in two parts, hinged together, he would not have time to open the hank so as to free the sail.

The guard also serves to support the roller-spindle, and to prevent it from wearing endwise through the hank.

While the rivets hold the legs of the bow A together, and prevent them from being split by the spindle when there is a great strain upon it, they also serve to sustain the spindle so as to prevent it from wearing down into the wooden bow.

The guard also prevents the wooden bow from spreading apart under the strain of the sail.

This sail-hank has been highly approved by nautical men, and on practice is found to be all that is desirable, and far preferable to many others in use. It is very desirable, cheap of construction, and not easy to get out of order.

What I claim as my invention, is—

The arrangement, as described, of the metallic guard D and rivets *b b*, with the roller-spindle C and the wooden bow A, the same being productive of an improved manufacture of sail-hank, provided with a friction-roller, as set forth.

WILLIAM MCKAY.
